To all whom it may concern:

Be it known that I, RUBY T. Fig. 1 is a plan view, and

Fig. 2 is a front view of a bottle or similar perfume container, showing my new design.

The floral design as it appears in the inner circle in Fig. 1 is painted on the upper surface of disk shown in broken lines in the bottom of the bottle in Fig. 2. The cut sides of the bottle constitute prisms which produce the effect shown in Fig. 1.

I claim:

The ornamental design for a bottle or similar perfume container, as shown and described.
